UNITED STATES PATENT OFFICE

BENJAMIN CUSHING, OF NORWOOD, MASSACHUSETTS

END CAP FOR TUBULAR PACKAGES

Application filed August 9, 1930. Serial No. 474,037.

This invention relates to a package prepared for shipment, storage, and sale, and including sheet material, such as felt or paper roofing, or floor-covering, such as so-called oil cloth, known under various trade names, the sheet being of indeterminate length, and wound to form a tubular roll.

The package in some cases includes a tubular core on which the sheet material is wound, 10 said core constituting a member of the package, and forming the internal surface thereof. In other cases the core is omitted, the inner convolution of the rolled sheet forming the internal surface of the package. The 15 ends of the package are protected by end caps including heads, formed to cover the package ends, and plugs fixed to the heads and inserted in the end portions of the internal surface of the package, and engaged 20 therewith to confine the heads against the ends of the package.

The invention is an improvement on that disclosed by my Patent No. 1,739,291, dated December 10, 1929, the device of that patent 25 being a protective end cap comprising a head formed to cover an end of a tubular package, and a tubular metallic plug fixed to the head and adapted to enter and frictionally engage an end portion of the internal surface of the 30 package, the plug being composed of a plurality of metal rings and metal holding members fixed within the rings and spacing the same apart, the holding member having attaching means engaged with the head.

The object of the present invention is to 35 provide a protective end cap which is simpler and of less expensive construction than my patented cap, and is not less efficient.

The invention is embodied in an end cap 40 which includes a metallic plug characterized as hereinafter stated.

Of the accompanying drawings forming a part of this specification,—

Figure 1 is a side view, showing a package 45 which includes a pair of protective end caps embodying the invention, and a core shown partly in section, the rolled sheet being shown by broken lines.

Figure 2 shows in section one of the end 50 caps on a larger scale, the plug being inserted

in the interior of the rolled sheet shown by broken lines.

Figure 3 is a perspective view of the end cap shown by Figures 1 and 2.

Figure 4 is a view similar to Figure 2, 55 showing a different form of the head.

Figure 5 shows in perspective one of the fasteners shown by Figure 4, before it is completed.

Figure 6 is a view similar to Figure 4, 60 showing a modification.

The same reference characters indicate the same parts in all of the figures.

The package with which my improved end cap is used may include a tubular core 12 65 (Figure 1), usually of stiff paper board, and sheet material 13, wound in a roll on the core. The core and the end caps engaged with its ends, constitute a spool, the length of which depends on the width of the sheet material 70 wound thereon. If a core is not employed, the internal surface of the package is formed by the inner convolution of the rolled sheet, as indicated by Figure 2. The rolled sheet is shown by broken lines in Figures 1 and 4. 75

The end cap, as in my former patent, includes a head 14, which is formed to cover an end of the package, and may be a disk of stiff paper board, or any other suitable material.

The improved cap embodying the present 80 invention includes also a one-piece cylindrical sheet metal tube 15, constituting a plug projecting from one side of the head and adapted to enter and frictionally engage an end portion of the package.

The plug 15 is provided with integral stiffening means opposing distortion or denting of the plug, said means being preferably embodied in spaced apart ribs 16, extending about the periphery of the plug, an annular inner flange 17, projecting inwardly from the inner end of the plug, and an annular outer flange 19, which may project outwardly from the outer end of the plug, as shown by Figures 1, 2, 3 and 6, or inwardly, as shown by Figure 4. Said flanges are in planes at right angles to the axis of the plug. I am enabled, by providing the said stiffening means, to make the plug from sheet metal or considerably less thickness than that required for 95 100

the rings and the metal holding members disclosed by my former patent, and to make the entire plug in one piece, instead of a plurality of pieces as heretofore, the plug being made by bending a single sheet blank and uniting the meeting edges of the blank by any suitable means such as rivets 18 (Figure 3), or seaming, or electric welding.

The outer flange 19 is seated on the inner side of the head 14 and constitutes an element of means for securing the plug to the head. Other elements of said means may be fasteners of any suitable type extending through the head 14 and flange 19, and seated on the outer surface of the head and on the inner surface of the flange to clamp said head and flange together. Said fasteners are here shown as wire staples including necks 20, and legs or prongs 21. The necks are seated on the outer side of the head 14, and the legs pass through the head and the flange 19, and their bent ends are seated on the inner side of the flange. Any other form of fastener adapted to clamp together the head 14 and flange 19 may be employed.

The plug 15 is provided also with spurs 22, forced outward from the periphery of the plug between its ends and adapted to automatically engage the internal surface 30 of the package. The spurs 22 are inclined as indicated by Figures 2 and 3, to permit inward movement of the plug into the package, and oppose the withdrawal of the plug from the package.

35 The disk 14 may constitute a flat-sided inner portion of the head, and the head may include also an outer buffer portion bearing on the outer side of the said inner portion, and of smaller diameter than the latter, as shown by Figures 4 and 6.

Figure 4 shows a buffer portion 24, composed of a plurality of disks of fibrous material, such as paper, said disks being bound together and secured to the inner head portion 14 by fasteners which may be the above described staples, or of any other suitable character.

Figure 6 shows a buffer portion composed of a dished sheet metal body 25, and a flange 26, attached to the head portion 14 and the tube flange 19 by staple-shaped or other fasteners.

The outer margin of each of said buffer portions has a smaller diameter than the inner head portion 14, and is arranged to sustain shocks or jars such as may be caused by rough handling of the package, and transmit the same directly to the wall of the tube 15, and at the same time, protect the relatively thin margin of the inner head portion 14.

This application is a continuation in part of my application filed February 13, 1930, Serial No. 428,055.

I claim:

1. A protective end cap comprising a head formed to cover an end of a tubular package, and a tubular sheet metal plug formed to bear on an end portion of the internal surface of such package, and having annular outer and inner stiffening flanges, the outer flange being seated on the inner side of the head and the inner flange projecting inwardly from the periphery of the plug, and fastening means securing the outer flange to the head, the head including a flat sided inner portion of greater diameter than the plug and bearing on the said outer flange, and an outer buffer portion bearing on the outer side of said inner portion and of smaller diameter than the latter, the outer margin of said buffer portion being arranged to sustain shocks or jars, transmit the same directly to the wall of the plug, and protect the margin of the inner portion. 70

2. A protective end cap comprising a head formed to cover an end of a tubular package, a tubular sheet metal plug formed to enter and bear on an end portion of the internal surface of such package and having outer and inner stiffening flanges in planes at right angles to the axis of the plug, the outer flange bearing on the inner side of the head, and fastening members clamping the head and the outer flange together, the inner flange 90 projecting inwardly from the inner end of the plug and resisting pressure tending to collapse said inner end, the outer flange, the head and the fastening members resisting pressure tending to collapse the outer end of the plug, the plug being provided with spurs projecting outwardly from its periphery and adapted to automatically engage the internal surface of the package, said spurs being inclined relative to the axis of the plug to permit inward movement on the plug into the package and prevent the withdrawal of the plug therefrom. 95

3. A protective cap of the character and for the purposes set forth comprising a plug element adapted to enter one end of the bore of a tubular package, a head element projecting radially from said plug to overlap the end of such a package, and a buffer element at the outer side of said head and of less diameter than the head, and otherwise of such dimensions as to sustain the shocks or jars of impact applied endwise of the package and at an inclination to its axis. 110

In testimony whereof I have affixed my signature.

BENJAMIN CUSHING.
